UNITED STATES PATENT OFFICE.

CATHERINE VERONICA RYAN, OF QUINCY, ILLINOIS.

DESIGN FOR AN INDIVIDUAL COFFEEPOT.

Application filed March 28, 1928. Serial No. 28,042. Term of patent 7 years.

To all whom it may concern:

Be it known that I, CATHERINE V. RYAN, a citizen of the United States, resident of Quincy, in the county of Adams and State of Illinois, have invented a new, original, and ornamental Design for an Individual Coffeepot, of which the following is a specification, reference being had to the accompanying drawing, forming part thereof.

The figure is a perspective view of an individual coffee pot, showing my new design.

I claim:

The ornamental design for an individual coffeepot, as shown.

CATHERINE VERONICA RYAN.
